MACHINE FOR MELTING SNOW

Filed Dec. 11, 1928

Inventor:
Peter LaCourt,
by Wright Brown (Signed May 27)
attys.

UNITED STATES PATENT OFFICE

PETER LA COURT, OF BOSTON, MASSACHUSETTS

MACHINE FOR MELTING SNOW

Application filed December 11, 1928. Serial No. 325,345.

This invention relates to machines for removing snow from streets, sidewalks, etc., by heat developed by burners consuming liquid fuel, the machine including a row of 5 burners adapted to project jets of flame while traveling over a surface to be cleared of snow.

The object of the invention is to provide a machine, the burners of which are independently controllable, each burner forming an 10 element of a snow-melting unit which can be made operative and inoperative and regulated independently of the others.

Of the accompanying drawings forming a part of this specification,—

15 Figure 1 is a top plan view of a machine embodying the invention.

Figure 2 is a side view of the same.

Figure 3 is a fragmentary view, showing in perspective portions of one of the units 20 of the machine and including a diagram illustrating the electric circuit of the ignition system.

Figure 4 is a fragmentary sectional view, showing one of the blow torches or burners.

25 Figure 5 is a view similar to Figure 4, showing a shield associated with the blow torch.

Figure 6 is a section on line 6—6 of Figure 5.

30 The same reference characters indicate the same parts in all of the figures.

The machine includes a frame which, in this instance, includes side members 12, a front transverse member 13, and a rear transverse member 14, the latter having bearings 35 for the burner and igniter shafts hereinafter described. The frame is supported by relatively large forward wheels 15, mounted on axles carried by the side portions and smaller 40 rear wheels 16, mounted on axles carried by adjustable arms 17, pivoted at 18 to the frame and adjustably confined by rods 19, which are adjustable in ears 20 on the frame to raise and lower the rear wheels and thus 45 vary the inclination of the frame.

21 designates a tank supported by the rear portion of the frame and adapted to contain gasoline or other liquid fuel. Air pressure may be maintained on fuel in the tank by an 50 air pump 22 connected therewith. 23 des-

ignates a fuel-supply pipe extending across the frame at the front end portion thereof, and connected with the tank, in this instance, by a pipe 24 connected with the bottom of the tank and pipes 25 connected with the ends of the tank. Connected with the supply pipe 23 are burners of the Bunsen type, each including an inner nozzle 26 (Figure 4), whose bore is connected by a duct 27 with the pipe 23, and a mixing nozzle 28 secured to and projection from the inner nozzle and provided with orifices 29, said nozzles projecting forward from the pipe 23 and being inclined downward. Each burner is provided with a screw-threaded needle valve 30, engaged with a tapped socket 31 in alignment with the bore of the nozzle 26, and adapted to be turned in the socket to open, close and adjust the valve. When the valve 30 is opened a jet of fuel is projected forwardly by the burners by air pressure in the tank.

Below each burner is a drip pan 32 which receives liquid fuel from the burner when the valve 30 is opened. Each drip pan is provided with an igniter which includes a fixed member 33 and a movable member 34. Said members are, in this instance, sparking electrodes connected in an electric circuit which includes a battery 35 and a transformer 36. The movable electrode 34 is fixed to a short shaft 37 journaled in a fixed bearing 38. The turning of the shaft 37 causes a wiping contact of the electrode 34 with the fixed electrode 33, and the production of a spark when the electrodes separate. The spark ignites liquid fuel in the pan 32 and this ignites the fuel projected by the burner. 39 designates a valve-operating shaft connected with the needle valve 30 by a flexible joint 40, and of any suitable construction whereby when the shaft is turned, the valve is also turned to regulate the flame or shut it off. The shaft 39 is inclined upwardly and extends through a bearing in the elevated frame member 14, so that its rear end which is provided with a handle, may be conveniently manipulated by the operator to rotate the shaft. The inclination of the shaft 39 differs from that of the burner nozzle and its valve, and for this reason, a flexible joint at 40 is provided. The 100

short shaft section 37 carrying the movable sparking electrode, is connected by a flexible joint, shown conventionally at 42, with a longer shaft section 43, which extends beside the valve-operating shaft 39 and is journaled in a bearing in the frame member 14 and provided with a handle whereby it may be rotated. The joint at 42 should be constructed to permit a complete rotation of the shaft sections, the object of the joint being to permit different inclinations of the shaft sections as shown. The operation of each burner may be started by first slightly opening its valve by turning the shaft 39 to allow a small quantity of fuel to drop into the pan 32, and then operating the igniter by rotating the shaft sections 43 and 37 to create a spark, the arrangement being such that the spark ignites the fuel in the pan which ignites the fuel issuing from the burner. The burner valve is then adjusted to supply the quantity of fuel required to project a suitable flame.

It will be seen that each burner, its valve, valve-operating shaft, drip-pan, igniter and igniter-operating shaft constitute elements of an independently controlled unit which may be rendered operative and inoperative and regulated independently of the other units. This independence enables the operator to shut off one or more burners at one or both ends of the row, and otherwise control the burners. For example, in case the flame of any burner is extinguished and the fuel continues to flow, the igniter may be operated to re-ignite the fuel, or the valve may be closed.

The adjustability of the rear wheels 16 enables the inclination of the frame and the burners, and the height of the burners above the surface on which they act, to be varied.

A U-shaped windshield 45, shown by Figures 5 and 6, may be attached to the burner, as by studs 46 (Figure 6), the shield being spaced from the mixing nozzle 28, and projecting from the front end thereof. The shield protects the projected flame from wind, tending to blow or deflect the flame from the predetermined direction.

I have shown only one of the burners provided with the shield 45, this being the upper burner shown by Figure 1. It is obvious, however, that a shield may accompany each burner.

I claim:

A snow-melting machine comprising a wheeled frame, a supply tank supported by the frame, means for exerting pressure on liquid fuel in the tank, a fuel supply pipe connected with the tank and extending across the forward end of the frame, a row of inclined burners connected with the supply pipe and arranged to forwardly and downwardly project jets of fuel, valves controlling the burners, drip pans under the burners, igniters arranged to ignite liquid fuel

in the pans to ignite jets emitted by the burners, each igniter including a movable and a fixed member, valve-operating shafts connected with the controlling valves, igniter-operating shafts connected with the movable members of the igniters, said shafts extending to the rear portion of the frame, and means at said rear portion for operatively supporting said shafts, each burner and its valve, the igniter, and the valve and igniter shafts associated therewith, constituting elements of a unit which is operable independently of the other units.

In testimony whereof I have affixed my signature.

PETER LA COURT.
